TICKET BOOK

John A. Bryce, Newark, N. J., assignor to International Ticket Company, Newark, N. J., a corporation of New Jersey

Application May 7, 1938, Serial No. 206,542

3 Claims. (Cl. 283—6)

This invention relates to ticket books provided with a plurality of leaves which are each subdivided to provide a retained record stub and a detachable coupon section, the latter having a tongue portion upon which is carried an initially concealed inscription; said leaves being so bound into the book that the inscription on the detachable coupon sections are initially invisible and are not intended to be disclosed until the tongue portions bearing the same are withdrawn from the binding by detachment of the coupon sections.

In ticket books of the kind above mentioned, as heretofore provided, it has been found that after a certain number of the coupon sections and their tongue portions have been detached and withdrawn from the book, it is possible to so manipulate the book that the inscription on the tongue portion of an undetached coupon section, which is intended to be concealed until after the coupon section is detached, may be rendered visible before such detachment. This is done by inserting a pencil, or like leverage exerting instrument, beneath the bound portion of the cover, and thereupon utilizing the same as a lever to transversely flex this portion of the cover and also, to some extent, the butt portions of the remaining leaves, to thereby pry apart these portions sufficiently to permit sight of the inscription otherwise concealed. It is an object of this invention to provide, in a ticket book of the kind mentioned, additional guard means calculated to prevent manipulations of the kind described or other undesired manipulations likely to permit visibility and disclosure of the concealed inscriptions prior to the detachment and withdrawal of a coupon section with which it is associated.

Other objects of this invention, not at this time more particularly enumerated, will be understood from the following detailed description of the same.

An illustrative embodiment of this invention is shown in the accompanying drawings, in which:

Fig. 1 is a front face view of a ticket book, made according to this invention, in closed condition; Fig. 2 is a horizontal section, showing the form and arrangement of the book leaf having the record stub and detachable coupon section provided with the tongue portion carrying a desired initially concealed inscription; Fig. 3 is a side edge elevation of the ticket book in closed condition; Fig. 4 is a horizontal section in the plane of a guard means element with which the book is provided; Fig. 5 is a longitudinal section through the ticket in open condition, and show-

ing the condition of the same after some of the coupon sections have been withdrawn, and the relation of the guard means element to the remaining butt portions of the leaves from which the coupon sections have been detached; and Fig. 6 is a transverse section, taken on line 6—6 in Fig. 5.

Similar characters of reference are employed in the above described views, to indicate corresponding parts.

Referring to the drawings, each leaf of the book comprises a butt portion 10, integral with which, for outward extension therefrom, is record stub section 11 and a detachable coupon section 12. Integral with the inner end of the detachable coupon section 12 is an inwardly projecting tongue portion 13 which indents the body of the butt portion 10. The record stub section 11 may be provided for the entry thereupon of such record data as are desired. The coupon section 12 may have printed thereon such descriptive matter as is desired, and on the extreme end of the tongue portion 13 is printed the inscription 14 desired to be initially concealed. To hold the coupon section 12 and its tongue portion 13 initially secured to the butt portion 10 and the associated record stub section 11, the leaves are provided with scores or interrupted slits 15 intermediate these parts, integral coupling necks 16 which retain the parts together being provided in the lines of said slits. By the latter arrangement, when an outward pulling strain is exerted upon the coupon section 12 and its tongue portion 13, the coupling necks 16 will part thus detaching the coupon section 12 for removal with accompanying outward withdrawal of the tongue portion 13 thereof, whereupon the concealed inscription borne by the latter portion will be disclosed to the possessor of the thus detached coupon section.

In making up the ticket book a desired number of leaves, characterized as above described, are arranged in superimposed registered relation, the total number of leaves is subdivided into groups of a selected number so as to form the same into piles of minor thickness, and interposed between these piles and guard members of relatively heavy and tough sheet material, such as comparatively heavy paper. The guard members each comprise a guard portion 17 to register with the butt portions 10 of the book leaves and a detachable spacer portion 18 to register with and lie between the outer portion of the leaves comprising the record stub and detachable coupon sections 11 and 12. A scored or

rouleotted line 19 is provided intermediate the guard portions 17 and spacer portions 18 of the guard members, thus weakening the latter along such lines to permit the spacer portions 18 to be torn away and detached when desired.

5 The book leaves with suitably interposed guard members are arranged between top and bottom cover members 20 and 21, and thereupon bound together and between said cover members by 10 clinched binding staples which are passed through the butt-portions of the thus assembled book parts. In preferred arrangement a pair of longitudinally spaced staples 22 are positioned more or less parallel and adjacent to the upper longitudinal 15 margins of the tongue portions 13 which indent the butt portions 10 of the leaves; and in like manner a second pair of longitudinally spaced staples 23 are positioned more or less parallel and adjacent to the lower longitudinal margins 20 of said tongue portions; while a transversely disposed staple 24 is positioned adjacent to the terminals of said tongue portions. This arrangement and disposition of the staples 22, 23 and 24 firmly secures the butt portions of the leaves, 25 guard members and cover members together and in bound relation, while leaving the tongue portions 13 free to break away and withdraw from the leaf butt portions when the detachable coupon sections are torn away and withdrawn end- 30 wise from the book.

When the coupon sections of the upper pile of book leaves have been detached and withdrawn so as to expose an underlying guard member, the spacer portion 18 of the latter is torn away to 35 expose the ticket leaves of the underlying pile thereof. As the coupon sections of the latter pile are successively detached and withdrawn, the overlying guard portion 17 effectively prevents the insertion of a leverage instrumentality be- 40 tween the butt portion of the upper cover portion and the remaining book leaves, or between said guard portion 17 itself and said remaining book leaves, in an attempt to pry up and flex either of the same sufficiently to permit sight of the 45 inscription of the tongue portion of the exposed coupon section prior to the detachment of the latter.

It will be obvious that the number of guard members employed in a given book will depend 50 more or less upon the thickness of the book, in other words, upon the total number of leaves included in the book. For best results the total number of book leaves will be divided into a plurality of relatively thin piles separated one from the other by the interposed guard members.

55 Having thus described my invention, I claim:
1. A ticket book comprising a plurality of su-
perposed leaves, each comprising a butt portion

and an outlying extension subdivided to provide a non-detachable record stub section and a detachable coupon section having an inwardly projecting concealed inscription bearing tongue portion indenting said butt portion, said leaves being arranged in segregated groups, guard means of comparatively stiff sheet material interposed between the leaf butt portions of said groups, cover means enclosing said leaves, and binding staples engaged through the inner end portions of said cover means and through said leaf butt portions and guard means in surrounding but outwardly offset relation to the inscription bearing tongue portions which indent said leaf butt portions.

2. A ticket book comprising a plurality of su- 15 perposed leaves, each comprising a butt portion and an outlying extension subdivided to provide a non-detachable record stub section and a detachable coupon section having an inwardly projecting concealed inscription bearing tongue portion indenting said butt portion, said leaves being arranged in segregated groups, guard means of comparatively stiff sheet material interposed between the leaf butt portions of said groups, said cover means enclosing said leaves, and binding staples engaged through the inner end portions of said cover means and through said leaf butt portions and guard means in surrounding 20 but outwardly offset relation to the inscription bearing tongue portions which indent said leaf butt portions.

3. A ticket book comprising a plurality of su- 35 perposed leaves, each comprising a butt portion and an outlying free extension subdivided to provide a non-detachable record stub section and a detachable coupon section having an inwardly projecting concealed inscription bearing tongue portion indenting said butt portion, said leaves 40 being arranged in segregated groups, guard means of comparatively stiff sheet material interposed between the leaf butt portions of said groups, said guard means having detachable spacer portions to lie between the outlying leaf extensions of said groups, cover means enclosing said leaves, and binding staples engaged through the inner end portions of said cover means and through said leaf butt portions and guard means in surrounding 45 but outwardly offset relation to the inscription bearing tongue portions which indent said leaf butt portions.

JOHN A. BRYCE.
